UNITED STATES PATENT OFFICE.

CLARENCE H. HOWARD, OF ST. LOUIS, MISSOURI, ASSIGNOR TO COMMONWEALTH STEEL COMPANY, OF ST. LOUIS, MISSOURI, A CORPORATION OF NEW JERSEY.

CAR SIDE-DOOR-FRAME BOTTOM MEMBER.

1,074,793.

Specification of Letters Patent.

Patented Oct. 7, 1913.

Application filed June 21, 1912. Serial No. 705,065.

To all whom it may concern:

Be it known that I, CLARENCE H. HOWARD, a citizen of the United States, residing at St. Louis, Missouri, have invented 5 a certain new and useful Improvement in Car Side-Door-Frame Bottom Members, of which the following is a full, clear, and exact description, such as will enable others skilled in the art to which it appertains to 10 make and use the same, reference being had to the accompanying drawings, forming part of this specification, in which—

Figure 1 is an elevational view of a car side door frame bottom member of my improved construction. Fig. 2 is an elevational view of a modified form of the bottom member. Fig. 3 is a vertical section taken on the line 3—3 of Fig. 1. Fig. 4 is a vertical section taken approximately on 20 the line 4—4 of Fig. 2. Fig. 5 is a perspective view of the end portion of the form of bottom member seen in Fig. 1. Fig. 6 is a perspective view of the form of bottom member seen in Fig. 2.

25 This invention relates generally to railway car construction, and particularly to the bottom member of a railway car side door frame.

In cars having comparatively deep continuous side sills extending from the floor level to the window sills, the greater portion of the load of the car is carried by said sills, but in cars having large side door openings such as baggage, express and mail cars, the door opening extends to the floor level or thereabout, thereby reducing the depth of the side sills.

Where cars are thus constructed, it is necessary that the sill members be reinforced 40 and strengthened immediately adjacent to the door openings in order to proportionately distribute the load-carrying strength of the side sills.

It is the principal object of my invention 45 to provide a one-piece cast metal member that will readily combine with the sill members of the underframe and bridge the space below the door openings, thereby strengthening and reinforcing the side sills.

50 Further objects of my invention are to provide a bottom member for a side door frame that can be readily combined with either a continuous side sill or with a side sill that is formed in sections, the ends of 55 which terminate at points below the door

posts, and further to construct a bottom member with short upright extensions to which the lower portions of the door posts are attached.

To the above purposes my invention consists in certain novel features of construction and arrangement of parts hereinafter more fully described and claimed.

The form of bottom member illustrated in Figs. 1, 3 and 5 is intended particularly for use in connection with a side sill that is made in sections, the same terminating at points substantially below the sides of the side door opening, and in this form of the member 1 designates a flanged rail, preferably channel-shaped in cross section and having a length sufficient to bridge the space between the ends of the sections of side sills A. The end portions of this bottom member, overlap the ends of the side sills and are 75 fixed thereto, preferably by means of rivets.

Formed integral with the rail 1 and projecting upwardly therefrom at points near the ends of said rail are short, vertically disposed posts 2, to which the lower ends of the 80 side door posts B are fixed.

Formed within the rail 1 between the posts 2 and suitably spaced apart are integral reinforcing webs or flanges 3.

The form of bottom member illustrated 85 in Figs. 2, 4 and 6, is particularly designed for use in connection with a continuous side sill, and in this form, the rail 1^a is provided in its outer face with a longitudinally extending recess 1^b which receives one of the flanges of the continuous side sill C. In this form of bottom member the end portions of the rail 1^a are fixed to the side sill C in any suitable manner, preferably by means of rivets, and likewise the lower ends of the side 95 door posts are fixed to the upper ends of the short vertical posts or extensions 2^a.

A side door frame bottom member of my improved construction is comparatively simple, can be easily and cheaply manufactured, 100 and being formed in a single piece, can be readily combined with the side sill members and door posts of a car frame.

The rail forming the main body portion 105 of the device, bridges the space beneath the door opening, thereby materially strengthening the side sill below and adjacent to said opening, and the upright extensions on said rail provide means for readily attaching the lower portions of the door posts.

It will be readily understood that minor changes in the size, form and construction of the various parts of my improved side door frame bottom member can be made and substituted for those herein shown and described without departing from the spirit of my invention, the scope of which is set forth in the appended claims.

I claim:

- 10 1. A car side door frame bottom member cast in a single piece and comprising a pair of short, vertically disposed posts adapted to engage and be fixed to the lower ends of the car side door posts, a horizontally disposed rail integral with the lower portions of said posts, which rail is adapted to engage and reinforce the side sill of the car underframe and the ends of which rail extend beyond the short, vertically disposed 15 posts for attachment to the side sill of the car underframe.
- 20 2. In car construction, the combination with the underframe side sill and side door posts, of a sill reinforcing and post-attaching member comprising a rail adapted to be applied and fixed to the side sill beneath the 25

door opening, a pair of short, vertically disposed posts integral with said rail, which posts engage and are fixed to the lower ends of the side door posts, and the ends of which horizontally disposed rail project beyond the short, vertically disposed posts.

3. The combination with a car side sill and side door posts, of a sill-reinforcing and post-attaching member comprising a horizontally disposed rail that is channel-shaped in cross section and adapted to be applied to the side sill beneath the door opening which rail is of sufficient length to extend substantial distances beyond the ends of the 40 door opening, and short upright members on the end portions of said rail, the upper ends of which upright members are adapted to be engaged by the lower ends of the side door posts.

In testimony whereof I hereunto affix my signature in the presence of two witnesses, this 28th day of May, 1912.

CLARENCE H. HOWARD.
